Primary Examiner — Darlington Ly*Assistant Examiner* — Daniel J Domino(74) *Attorney, Agent, or Firm* — Finnegan, Henderson, Farabow, Garrett & Dunner LLP(57) **CLAIM**

The ornamental design for a display screen with graphical user interface, as shown and described.

DESCRIPTION

FIG. 1 is a front view of a display screen with graphical user interface, showing the new design;

FIG. 2 is a second embodiment thereof;

FIG. 3 is a third embodiment thereof; and,

FIG. 4 is a fourth embodiment thereof.

In the drawings, the showings of the display screen in dash-dot broken lines and portions of the graphical user interface in even broken lines do not form part of the claimed design.

1 Claim, 4 Drawing Sheets(56)
